UNITED STATES PATENT OFFICE

FAY D. KINNEY, OF SOUTHBIDGE, MASSACHUSETTS, ASSIGNOR TO UNITED SHOE MACHINERY CORPORATION, OF PATERSON, NEW JERSEY, A CORPORATION OF NEW JERSEY

FOXING CEMENTING MACHINE

Application filed October 16, 1929. Serial No. 400,130.

This invention relates to machines for applying cement to shoes and is herein illustrated as embodied in a foxing cementing machine of the type shown in United States Letters Patent No. 1,830,114, granted Nov. 3, 1931, upon my application, in the use of which machine cement is projected upon the exposed foxing area of a shoe which is protected above that area by a surrounding shield. An important object of this invention is to provide an improved machine of this general type.

In the manufacture of rubber soled tennis shoes, for example, it is the general practice to secure the margin of the sole to the upper of a shoe by means of an interposed strip of gum rubber called a foxing or a foxing strip which itself is secured to the canvas upper by a stripe of cement applied to the lower marginal portions of the sides of the upper. It is well understood in the art that the application of this stripe of cement, to prove commercially satisfactory, must be effected quickly and cheaply and in a thick coating. Furthermore, the upper margin of the stripe of cement should be accurately located at a substantially uniform distance from the bottom of the shoe in order to secure the whole width of the foxing strip without extending above it.

In machines of the type under consideration, the extent of the foxing area to be coated is determined by a cooperating shielding device having an aperture through which a portion of the shoe is moved to expose the foxing area to the action of cement applying means while the remainder of the shoe is protected by said apertured shielding device. Proper protection of a shoe demands relatively close cooperation between the shielding device and the shoe. Moreover, the run of work in any shoe factory includes shoes of radically different sizes and styles. In view of these considerations, the machine herein illustrated, in accordance with a feature of the invention, is provided with a shielding device which is made up of a plurality of movable sections overlapping at their ends, each section being flexible or dis-

different sizes and styles. As illustrated, the various sections of the shield are mounted on slides so that they may be moved away from the shoe to open up the shield or moved into cooperative relation with the shoe as the shield is closed. The end sections of the illustrated shield are constructed and arranged to be wrapped around the toe and heel portions of the shoe.

In accordance with other features of the invention, the illustrated machine comprises a shoe ejector movable to carry a shoe out of range of the cement applying means and baffles are provided which may be interposed between the cement applying means and the shoe during the time interval when one shoe is being removed and another put in its place. As illustrated, automatic mechanism is provided for opening and closing the shield, raising and lowering the baffles and ejecting the coated shoe from the machine, all in proper timed relation.

As in the machine illustrated in United States Letters Patent No. 1,830,114 referred to, the illustrated machine is provided with a receptacle positioned beneath a shoe support and cement is projected in a spray upon the unprotected foxing area of the shoe by rotary cement projecting devices. Still another feature of the invention resides in improved rotary projecting devices which operate by centrifugal force both to lift the cement from the receptacle and to project it upon an article to be coated. In the illustrated embodiment of the invention, these projecting devices are supported on the lower ends of vertical shafts and each comprises a cement feeding member in the form of a hollow member open at the bottom and dipping in the liquid in the receptacle, the hollow member being provided with a peripheral outlet adjacent to its upper end. This hollow member is herein illustrated as frustoconical and thus having a continually increasing diameter so that, under the action of centrifugal force, the liquid is impelled to travel up the inner surface and is projected out of the peripheral outlet between the hollow member and a disk by which it is supported on its shaft. The tendency of such a rotary

- member to push the body of the cement away from its lower end, because of the friction between its outer surface and the cement, is overcome in the illustrated construction by 5 providing a stationary baffle herein shown as a frusto-conical member surrounding and positioned close to the outer surface of the rotary cement applying member to resist the circulation of the liquid in the receptacle.
- 10 Provision is made, in the illustrated construction, for supporting a shoe in predetermined relation to the lower edge of the shielding device which as shown is brought into contact with the shoe at the upper edge of the 15 foxing area. This shoe support is mounted for independent up-and-down adjustment of its ends. By means of this arrangement, it is possible adjustably to determine the width of the foxing area to be coated.
- 20 These and other features of the invention are more fully set forth in the accompanying description taken in connection with the drawings, in which
- Fig. 1 is an end elevation of the machine 25 with parts broken away and in section;
- Fig. 2 is a side elevation of the machine;
- Fig. 3 is a detailed view in section on the line III—III of Fig. 9 of one of the side plates of the shielding device taken from the 30 outside thereof;
- Fig. 4 is a fragmentary detail of a support for one of an end plate of the shielding device;
- Fig. 5 is a plan view of the machine;
- 35 Figs. 6 and 7 are plan views of the central portion of the cover of the machine including the shielding devices supported thereon, with parts broken away;
- Fig. 8 is a transverse section through the 40 cover near one end to show the slide which supports one of the end shields;
- Fig. 9 is a plan view, on a larger scale, of the two side plates and the underlying work support;
- 45 Fig. 10 is a transverse central vertical section through the side plates and their supporting slides; and
- Fig. 11 is a longitudinal central vertical section through the end shield plates and their 50 supporting slides.
- A piece of work, such as a lasted tennis shoe 10, is presented to the machine by being lowered through an opening in a top cover 12 (Fig. 5) of a frame 14 and rested upon 55 a work support 16 (Fig. 2). In this position the upper part of the shoe which is not to be coated is surrounded by a shielding device comprising a pair of side pieces 18 (Fig. 5) and a pair of end pieces 20 and cement picked 60 up from a receptacle 22 (Fig. 1) is applied to the exposed foxing area of the shoe by means of four symmetrically positioned rotary spraying devices 24 (Figs. 1 and 5) which are effective simultaneously to coat the 65 whole of the foxing area. After a sufficient

quantity of cement has been applied, the machine operates automatically to raise a pair of baffle plates 26 (Fig. 1) which are interposed between the spraying devices and the shoe and to open the shielding devices; 70 the machine then operates, by means of an ejecting grid 28 (Fig. 2) which is raised mechanically, to lift the shoe out of the machine to a position where it may be removed manually or received by a transferring mechanism of the kind illustrated in United States Letters Patent No. 1,850,151, granted March 22, 1932, upon my application. After this the ejecting grid is carried back to its original position and the machine stops, it being 75 understood, however, that the spraying devices are rotated continually during the period of use of the machine.

The frame 14 is a box-like structure having a large opening 30 (Fig. 2) at one side 80 which is closed by a pair of doors 32 (Fig. 1). Within this frame is an electric driving motor 34 carrying a pulley 36 which is belted to a pulley 38 on a counter shaft 40. From this counter shaft the various spraying devices 24 85 are driven by means of round belts 42. The motor shaft is connected through an Oldham coupling 44 to a short shaft 46 carrying a worm 48. This worm, mounted within a suitable grease-containing casing 50, meshes with 90 a worm gear 52. The worm gear is mounted on a short shaft 54 (Fig. 2) which carries a small pinion 56 meshing with a larger gear 58 forming half of a clutch and mounted for free rotation upon a cam shaft 60. The other 95 half of the clutch which is of a construction essentially like that shown in United States Letters Patent No. 1,843,232, granted February 2, 1932, upon the application of B. Jorgensen, comprises a circular member 62, of 100 about the same size as the gear 58, which is keyed to the cam shaft 60 and carries a connecting device in the form of a pin 64 (Fig. 1) the inner end of which has a flattened face for engagement with ratchet teeth 66 formed 105 upon a ring within the gear 58. When the pin is in one position it connects the clutch parts and when the pin is in another position it rides freely past said teeth. The connecting pin 64 is provided with a short arm 68 110 to which there is secured a spring 70 urging said pin in such a direction that the clutch will be closed and the two parts 58 and 62 will rotate together. The pin 64 is also provided with a projecting stud 72 which extends 115 through a slot in the peripheral face of the clutch member 62 and is positioned for engagement by the upper end of a clutch disconnecting lever 74. This lever is journaled in the frame of the machine and urged in counterclockwise direction by a spring 76 to bring 120 the upper end into position to disconnect the clutch. The lower end of the disconnecting lever 74 is provided with a contacting piece 78 for engagement with a latch 80 on a trip 125

lever 82 pivoted at the bottom of the machine and connected through a rod 84 with a starting treadle 86, said latch being urged to the position shown in Fig. 1 by a suitable 5 spring 88.

The spraying members 24 which are on the near side of the machine as viewed in Fig. 1 are driven directly by a counter shaft 40, while those on the far side of the machine 10 are driven by another shaft 41 (Fig. 2) connected by a crossed belt 43. The cement receptacle 22 (Fig. 1) is partially filled with cement during the use of the machine and this cement is picked up by the driven spraying 15 devices and projected upon a shoe, any surplus draining back into the receptacle. At the close of the day's work, the cement may be removed from the receptacle through a suitable drain 90 extending out beyond the 20 frame to a point where the cement can easily be caught in a bucket and said drain passage is closed at its outer end by a flap 92.

The various spraying or projecting devices 24 are identical and each one comprises a flat 25 disk 94 (Fig. 1) mounted at the lower end of a driven shaft 96 extending up and down through bearings in a supporting arm 98 which is hinged on a lateral rod 100 so that the spraying device with its supporting arm 98 may be tilted back for cleaning. The driving belt of each spraying device extends 30 up over idlers 102 mounted on said lateral rod 100 and around a pulley 104 on the shaft 96 whereby the driving connection is not disturbed 35 when the spraying device is tilted back. A hinged cover 106 and an adjacent removable cover 108 (Fig. 5) bolted to the top of the frame of the machine, are provided completely to surround the driving 40 mechanism just described. The directions of rotation of the various spraying devices are indicated by arrows in Fig. 3 from which it will be seen that sprays are projected from the four corners of a rectangle toward the 45 shoe.

Each of the spraying devices picks up cement from the receptacle by means of an inverted frusto-conical hollow feeding member 110. This hollow feeding member 110 has an increasing diameter and extends upwardly toward the flat disk 94 and is flanged 50 at its upper end for attachment to the disk 94 near its periphery, said feeding member and said disk being separated by a narrow 55 peripheral slot through which the cement is projected by centrifugal force and applied to the work. The picking up of the cement from the receptacle by the hollow feeding member 110 results from the action of centrifugal force upon the cement resting 60 against the inner surface of said feeding member and urged upwardly along the inner sides thereof by reason of its constantly increasing diameter until the cement is thrown out of the peripheral slot.

65 It has been found that the friction be-

tween the outer surface of the feeding member 110 and the surrounding cement sets up a swirling action in the body of the cement which tends to cup out the cement and to hold it away from the lower open end of the hollow member. This action unhindered might be sufficient to prevent the cement from being picked up. The cupping action is effectively prevented, however, in the illustrated construction by baffles 112 associated with each of the spraying devices and illustrated as frusto-conical hollow members substantially parallel to the feeding members 110, said baffles being supported by lugs 114 from the bottom of the receptacle 22. These baffles prevent the swirling or cupping action just described and cause the cement to remain in contact with the lower end of the hollow members 110 so that it is fed up through said members continuously.

The shoe 10 as it rests upon the shoe support 16 must have a predetermined relation to the shields 18 and 20. Accordingly, the shoe rest 16, having a raised rib portion 120, is detachably supported at its ends by hangers 122 (Fig. 11), these hangers being in turn supported by levers 124 which are fulcrumed in the frame. Means is then provided for adjusting the position of the levers 124 to vary the position of the work support 16 comprising hand screws 126 and 128 acting in opposition to springs 130 surrounding the bolts on which the hand screws are threaded. A wedge shaped lever 132 (Figs. 5 and 11) is provided at the toe end of the shoe support to permit fine adjustments of this end of the shoe with respect to the shields to care for variations in "toe-spring" in shoes of slightly different styles. The shields 18 and 20 are slidably supported in the top cover 12 which has lateral lugs 134 (Fig. 10) for engagement with tapered studs 136 in the frame of the machine so that said cover may be lifted off the machine for cleaning purposes and readily replaced in position. The side shields 18, although of somewhat different shape, are substantially of identical construction and comprise thin plates, of brass, for example, each of which is secured to a casting 138 as by screws not shown. This casting has depending lugs 140 (Figs. 3 and 10) carrying a longitudinal rod on which are mounted distorting fingers 142, associated with each of which is a thumb screw 144 bearing against the under side of the casting 138 so that by adjusting said screws the shape of the shoe engaging edge of the shield 18 may be varied and more exactly determined to make it suit the particular style of shoe to be treated. Each of the castings is slotted at 146 (Fig. 9) for engagement with a stud carrying a thumb nut 148 so that the casting may be removably secured upon a slide 150.

Each of the slides 150 has a central rib 152 (Figs. 2 and 3) on its under face which is received in a slot 154 (Fig. 9) in the cover 130

12 and the slide is held in said slot by a plate 156 (Fig. 3) engaging the under side of the cover 12 and held in position on the slide by screws, of which one screw 158 (Fig. 9) has 5 an upstanding head for engagement with an operating lever 160 which is fulcrumed on a stud 162 (Fig. 7) in the top cover and which is operated in a manner to be later described to move the slide in and out substantially 10 radially of the shoe to bring the side shields 18 into cooperative relation with and preferably into contact with the shoe.

At the ends of the shoe are similarly shaped end shields 20 each of which is constructed 15 of thin sheet metal and is properly shaped at its lower edge so that when brought into engagement with the shoe, it will fit around the end of the shoe exactly at the top of the foxing area to protect the upper of the shoe above 20 that area. This end shield 20, instead of being shaped for exact engagement for any particular shoe, is supported at its center upon a slide 164 (Fig. 11) and at its ends by swinging paddle-shaped levers 166 (Fig. 6), the 25 arrangement being such that when the slide is moved forward the end shield will be caused to wrap itself around the curved end of the shoe either at the toe or the heel, as the case may be. Each end shield is centrally secured 30 to a casting 168 (Fig. 11) which is slotted so that it may be slipped into engagement with a depending stud 170 on the slide, and held there by a spring-pressed pin 172. In order to cause the end shields to wrap themselves 35 around the ends of the shoe, the machine is organized so that the central portion of the shield may be brought resiliently into contact with the shoe and additional movement then imparted to the end portions so that it 40 will wrap itself around the shoe. Accordingly, the slide 164 which supports the central portion of the shield is itself slidably mounted in another slide 174 which extends across the top cover 12 (Fig. 8) and is sup- 45 ported at its ends by underhanging strips 176 on said cover. These slides are also movable substantially radially toward and away from the shoe to move the shields into cooperative relation therewith. Additional sup- 50 port for the slide on the cover is secured by means of a centrally disposed casting 178 which is bolted to said slide and which travels in a slot 180 in the top cover and overhangs said top cover. Each end of the shield 20 is 55 attached to a block 182. The outer end of each block 182 is reduced in thickness to fit the space between the under face of the cover 12 and the paddle-shaped lever 166, and has a rib 183 (Fig. 4) sliding in an open ended 60 slot in one of the levers 166 as indicated by dotted lines in Fig. 7. This construction allows the ready removal of an end shield for cleaning or the substitution for one of different shape merely by raising the spring 65 pressed locking pin 172, after which said

end shield 20 may be moved endwise of the machine and disengaged from its central and end supports. Each of the paddle-shaped levers 166, by means of which these end supporting blocks 182 are carried, is pivoted at 70 188 upon a resiliently supported bolt 190 (Figs. 6 and 8) which slides within a tube 192 containing a spring 194. A stop nut 196 limits the inward movement of each of these bolts 190. Beside this pivotal support for the 75 paddle-shaped levers 166, it will be seen that the slide 174 is provided with ledges 198 underlying the levers and that the levers pass through slots 200 in the slide 174 formed by grooves therein and cover plates 202 screwed down to the slide. The portions of the levers 166 which extend into these slots are formed into narrow tails 204 interconnected at each end of the machine by springs 206, these 80 springs tending to swing each of the levers 166 in a direction to open the outer ends of the shield 20. The slides 164 and 174 are further interconnected for the purpose of operating the end shields by means of a bolt 210 (Fig. 11) which is secured to an upstanding portion of the slide 164 and which slips freely through an opening 212 (Fig. 8) in an upstanding portion 214 of the casting 178 on the slide 174. A spring 216 (Fig. 11) surrounding this bolt 210 tends to throw the 85 slide 164 forward to the limit permitted by lock nuts 218 on the bolt 210, but permits additional movement of the slide 174 to wrap the ends of a shield around the shoe after the central portion thereof has contacted with the shoe. It will be understood that this 90 wrapping action is facilitated both by the pivotal mounting of the supporting levers 166 and by the fact that each of these levers is mounted on a resiliently supported bolt 190. 95 100 105

In order to provide for the conjoint operation of the various shields 18 and 20 to bring them inwardly into cooperative relation with the shoe or to move them outwardly to permit the removal of the shoe, a connection is 110 provided between each of the operating levers 160 associated with the side shields 18 and the slides 174 associated with the end shields 20. This connection is in the form of a bolt 220 (Fig. 7) slidably mounted in a swivel block 222 carried at the end of a lever 160 and pivotally secured at 224 to an ear 226 (Figs. 1 and 8) upon the casting 178, 214 which is bolted to said slide 174. A spring 228 (Fig. 7) surrounding said bolt 220 provides a resilient connection between an end slide and a lateral slide so that there is freedom of movement and no danger of injury to the shoe. Power for moving the slides is delivered to the end slides through an upright pivot stud 230 (Fig. 11) on which is detachably mounted a bolt 232. This bolt is removably secured to the stud 230 by means of a swinging cap piece 234 (Fig. 5) held in position by a wing nut 236. Each of 115 120 125 130

the bolts 232 has a clamp nut 238 at its outer end and is surrounded by a spring 240 (Fig. 2) through which movement is imparted to the bolt 232 and hence to the slides by one 5 of a pair of similar levers 242 (Fig. 5). These levers, the ends of which carry swivel blocks slidably mounted on the bolts, are secured to the upper ends of upright shafts 244 journaled in the frame of the machine and 10 provided at their lower ends with mitre gear connections 246 (Fig. 1) to a longitudinal shaft 248. It is not intended that this shaft 248 will have a full rotation but only that it shall be swung by means of a lever 250 having 15 at its outer end a cam roll 252 for engagement with a disk cam 254 (Figs. 1 and 2) mounted on the cam shaft 60. A single rotation of the cam shaft is effective, therefore, to move the slides to close the shields into engagement 20 with the shoe and then at a later time to open up the shields to the position shown in Fig. 7.

The baffle plates 26 which may be raised into the range of the spraying devices to prevent the spattering of cement when the shoe 25 is being presented or taken out are long rectangular plates which are interconnected at their ends by cross rods 260. Carrying-hangers 262 (Fig. 2) are secured to the cross rods and to the hangers there are rigidly secured 30 operating arms 264 (Fig. 5) which are clamped on the reduced upper ends of upright rods 266 (Fig. 2). These rods are slidably mounted in suitable bearings provided in the frame of the machine and in 35 protective casings 268 bolted to the ends of said frame. Each of these upright rods 266 has a cam roll 270 resting on a cam 272 secured to the cam shaft 60 and each of the rods is provided with a slotted guide 274 40 offset from the cam roll and surrounding the end of the cam shaft 60 outside of the cam 272. It is possible, therefore, by a single rotation of the cam shaft to cause the raising and the lowering of the baffle plates in a desired 45 timed relation to the other operations of the machine.

In order to lift the work out of the machine at the completion of the cycle, the ejector 28 in the form of a grid received in grooves in 50 the work support 16 is mounted at the upper end of an upright operating rod 276 (Figs. 1 and 2) guided in a truss 278 bolted to the frame of the machine. The upper end of the ejector rod 276 passes through a raised collar 280 at the center of the receptacle 22 so that there will be no leakage of cement at this point. At the lower end of the ejector rod 276 is a slide 282 which is guided by depending portions 284 of the truss 278 and which 55 is pivotally connected to a pitman 286. This pitman is secured to a crank 288 on a stub shaft 290 mounted in a standard 292 bolted in the frame of the machine and the stub shaft 290 carries a pinion 294 meshing with a large 60 gear 296 freely rotatable upon the cam shaft 65

60. The gear 296 is held against lateral displacement on said cam shaft by engagement of its hub with plates 298 and 300 each of which is pinned to the cam shaft and operates to control the movements of the gear 296. 70 The plate 300 carries a pin 302 spring-pressed outwardly away from the gear but capable of being pushed into engagement with a shoulder on said gear by means of a cam bracket 304 which is bolted to a part of the standard 292. Thus, during a limited portion of the rotation of the cam shaft 60, the pin 302 will be forced into engagement with the gear 296 to cause a partial rotation thereof. Because of the gear ratio between the gear 296 and the pinion 294 this limited movement of the gear 296 is effective to cause a complete rotation of the crank 288, thereby to move the ejector 28 upwardly to carry a shoe out of the machine and then to drop said ejector back into position within the grooves of the work support 16. At the completion of the limited movement of the gear 296 which is required for this action, it is stopped by a spring-pressed pin 306 pressed inwardly 90 against said gear by a cam face on the plate 298. After the gear 296 has stopped, pressure on the pin 306 is released.

In the operation of the machine, assuming that the receptacle 22 has been supplied with cement and that the operator has placed a shoe upon the work support 16, depression of the starting treadle 86 will cause engagement of the driven portion 62 of the clutch with the constantly rotating gear 58 thereby to give 100 the cam shaft 60 one complete revolution. It will be understood that the motor is operating constantly during the use of the machine and accordingly that the spraying devices 24 are being driven continually to pick up cement from the receptacle and project it in the form of a fine spray. The spray will be intercepted inwardly by the baffle plates 26 and outwardly by the receptacle 22. After the cam shaft is started, however, the shields 18 105 and 20 will be moved into engagement with the shoe by the operating levers 242 acting through the various slides and the intermediate levers 160. The baffle plates 26 will then be lowered so that the projected cement 110 may be applied to the exposed foxing area of the shoe without danger that any of the upper portion of the shoe will become coated and with assurance that the range of the foxing area will be exactly determined and 115 a heavy coating of cement applied. After a suitable interval the baffle plates will again be raised and the shields opened whereupon the ejector 28 will operate to raise the shoe 120 out of the machine and then to drop back in 125 its original position in the grooves of the work support 16.

It will be understood that, in various aspects, the invention is not limited to embodiment in the particular type of machine shown 130

and described, or to the performance of the particular operation referred to. The scope of the invention should, therefore, be determined by the accompanying claims when construed by reference to the prior art.

Having thus described my invention, what I claim as new and desire to secure by Letters Patent of the United States is:

1. In a cement applying machine, a receptacle for cement, a support for an article to be coated positioned above the cement in the receptacle, means for projecting cement upon an article positioned upon said support, and a baffle mounted for movement into the path of said projected cement completely to interrupt the application of cement to the work and to carry back into the receptacle the cement received on the baffle.
2. In a cement applying machine, a receptacle for cement, a support for an article to be coated positioned above the cement in the receptacle, means for picking up cement from said receptacle and projecting it upon an article to be coated, and a baffle mounted for movement into and out of the path of said projected cement wholly to interrupt the application of cement to the work and to carry back into the receptacle the cement received on the baffle.
3. In a cement applying machine, a receptacle for cement, a support for an article to be coated positioned above the cement in the receptacle, means for applying cement to an article on said support, and a work ejecting device for lifting an article from said support to eject it from the machine after it has been coated.
4. In a cement applying machine, a receptacle for cement, a support for an article to be coated, shielding means for protecting a portion of the article which is not to be coated, means for applying cement to the exposed portion of an article on said support, and means inoperative during the application of cement for lifting an article out of said shielding means for removal from the machine.
5. In a cement applying machine, a receptacle for cement, shielding means for protecting a portion of an article leaving exposed another portion which is to be coated, means for applying cement to the exposed portion of the article, means for supporting an article in predetermined relation to said shielding means, and positively operated means to lift the article out of the shielding means after the coating operation has been completed.
6. In a cement applying machine, a receptacle for cement, a support for an article to be coated positioned above the cement in the receptacle, means for projecting cement against an article on said support, and intermittently actuated means for lifting said article to position it out of the range of the projecting means.

7. In a cement applying machine, a receptacle for cement, a support for an article to be coated positioned above the cement in the receptacle, means for projecting cement upon said article, a movable baffle adapted to be interposed between said projecting means and said article, and means for raising an article which has been coated for removal from the machine.

8. In a cement applying machine, a receptacle for cement, a support for an article to be coated positioned above the cement in the receptacle, means for projecting cement upon an article to be coated, a movable baffle adapted to be interposed intermittently between the article and said projecting means, means for raising said article, and operating means constructed and arranged to move said baffle out of range of the projecting apparatus to permit the application of cement to the article, for returning it into range to intercept the cement projected, and for then raising said article out of the machine.

9. In a cement applying machine, a receptacle for cement, a support for an article to be coated positioned above the cement in the receptacle, means for projecting cement upon said article to be coated, means for protecting a portion of an article on said work support, a movable baffle adapted to be interposed intermittently between the article and said projecting means, means for raising said article, and operating means constructed and arranged to move said baffle out of range of the projecting apparatus to permit the application of cement to the article, for returning it into range to intercept the cement projected, and for then raising said article out of the machine.

10. In a cement applying machine, a receptacle for cement, a support for an article to be coated positioned above the cement in the receptacle, means for projecting cement upon said article, movable shielding means adapted to be moved into cooperative relation with an article on said work support to protect a portion of said article from the application of cement, a movable baffle adapted to be interposed between the projecting means and the article to interrupt the application of cement, and power-driven means for operating said shielding means and said baffle in timed relation.

11. In a cement applying machine, a receptacle for cement, a support for an article to be coated positioned above the cement in the receptacle, means for projecting cement upon said article, movable shielding means adapted to be moved into cooperative relation with an article on said work support to protect a portion of said article from the application of cement, a movable baffle adapted to be interposed between the projecting means and the article to interrupt the application of cement, and power-driven means

for moving said shielding means into cooperative relation to said article, for moving said baffle out of the range of said projecting means so as to permit the application of cement to the unprotected portion of the article, and for then returning said baffle to intercepting position and moving said shielding means out of cooperative relation with the article.

- 10 12. In a cement applying machine, a receptacle for cement, a support for an article to be coated positioned above the cement in the receptacle, means for projecting cement upon said article, movable shielding means adapted to be brought into cooperative relation with the article to protect a portion thereof from the application of cement, a movable baffle adapted to be interposed between said projecting means and said article
- 15 to interrupt the application of cement and removed to permit said application, means for lifting said article to carry it out of the machine, and operating means for moving said baffle and said lifting means in timed relation.

13. In a cement applying machine, a receptacle for cement, a support for an article to be coated positioned above the cement in the receptacle, means for projecting cement upon said article, movable shielding means adapted to be brought into cooperative relation with said article to protect a portion thereof from the application of cement, a movable baffle adapted to be interposed between said projecting means and said article to interrupt the application of cement and removed to permit said application, means for lifting said article to carry it out of the machine, and operating means for moving said shielding means, said baffle and said lifting means in timed relation.

14. In a cement applying machine, a receptacle for cement, a support for an article to be coated positioned above the cement in the receptacle, means for projecting cement upon said article, movable shielding means adapted to be brought into cooperative relation with said article to protect a portion of said work from the application of cement, a movable baffle adapted to be interposed between said projecting means and a piece of work on the work support to interrupt the application of cement and removed to permit said application, means for lifting said article to carry it out of the machine, and power-driven operating means constructed and arranged to bring said shielding means into cooperative relation with the article, to move the baffle out of the range of the projecting means, to return the baffle into the range of the projecting means, to move said shielding means away from the article, and then to lift the article out of the machine.

15. In a machine for applying cement, a receptacle for cement, and means rotatable

about a substantially vertical axis and dipping in the cement constructed and arranged to lift cement from the receptacle and to project it through the air toward an article to be coated.

70 16. In a machine for applying cement, a receptacle for cement, and rotary means dipping into the cement and operating by centrifugal force both to lift the cement from the receptacle and to spray it upon an article to be coated.

75 17. In a machine for applying cement, a receptacle for cement, and rotary means dipping in the cement and provided with a peripheral opening above the level of the cement, said rotary means being constructed and arranged to lift cement from the receptacle and to project it through said peripheral opening upon an article to be coated.

80 18. In a machine for applying cement, a receptacle for cement, a driven shaft rotatable about an up-and-down axis and having a free lower end above the cement, and means secured to the lower end of said shaft constructed and arranged to pick up cement from the receptacle and to project it upon an article to be coated.

85 19. In a cement applying machine, a receptacle for cement, and a driven shaft rotatable about an up-and-down axis positioned above said receptacle carrying at its lower end means dipping in the cement in the receptacle and constructed and arranged to project the cement upon a distant article to be coated.

90 100 20. In a cement applying machine, a receptacle for cement, and a driven shaft rotatable about an up-and-down axis and positioned above said receptacle, said shaft carrying at its lower end a hollow frusto-conical member dipping in the cement in the receptacle and constructed and arranged to project cement picked up from the receptacle upon an article to be coated.

105 21. In a cement applying machine, a receptacle for cement, and a rotatable hollow member substantially circular in cross-section and constructed and arranged to have its lower end dip in cement in the receptacle, said hollow member being constructed and arranged to lift cement through its hollow interior and to project the cement removed from the receptacle on to a piece of work to be coated which is out of contact with said cement on the hollow member.

110 115 120 22. In a cement applying machine, a receptacle for cement, a support for a piece of work to be coated positioned above the cement in the receptacle, and means rotating about a substantially upright axis and dipping in the cement in the receptacle constructed and arranged both to lift cement from the receptacle and to apply it to a piece of work on said support spaced a substantial distance from the rotating means, the sur-

plus cement draining back into the receptacle.

23. In a coating machine, a receptacle for liquid, and rotary means dipping in the liquid in said receptacle constructed and arranged to pick up liquid from the receptacle and to project it upon a piece of work, said means comprising a rotatable member of circular cross section and varying diameter whereby the action of centrifugal force is effective both to cause elevation of the liquid and its projection from the portion of largest diameter.

24. In a coating machine, a receptacle for liquid, and rotary projecting means dipping in the liquid in said receptacle constructed and arranged to pick up liquid from the receptacle and to project it upon a piece of work, said projecting means comprising a hollow member open at the bottom and dipping in the liquid in the receptacle and said member being provided with a peripheral outlet adjacent to its upper end for liquid traveling over its inner surface.

25. A machine according to claim 24 in which the hollow member is frusto-conical.

26. A machine according to claim 24 in which the hollow member is frusto-conical with its larger end upward.

30 27. A machine according to claim 24 in which said hollow member is supported from above the liquid.

35 28. A machine according to claim 24 in which said rotary projecting means comprises a circular supporting disk, the peripheral portion of which is spaced a short distance from the upper edge of the hollow member thereby to provide a peripheral slot.

29. In a spray coating machine, a receptacle for liquid, a driven up-and-down shaft supported above said liquid, a spraying device comprising a plate supported at the lower end of said shaft, and a cooperating feeding member constructed and arranged to elevate liquid from the receptacle to the spraying device rotated with said plate and having its upper surface spaced from the lower surface of the plate to provide a peripheral opening through which liquid is expelled.

50 30. A machine according to claim 29 in which the feeding member is supported from and driven by said plate.

31. A machine according to claim 29 in which the feeding member is hollow and has an increasing diameter upwardly toward the plate.

32. In a coating machine, a receptacle for liquid, rotary projecting means comprising a driven member above the liquid and a hollow member dipping in the liquid in the receptacle constructed and arranged to pick up said liquid and project it upon a piece of work, and a baffle supported adjacent to the outer surface of the hollow member to interrupt the circulation of liquid caused by the fric-

tion between the outer surface of said hollow member and the body of the liquid.

33. A machine according to claim 32 in which a portion of said baffle is parallel to the outer surface of the hollow member.

34. A machine according to claim 32 in which said baffle is supported by said receptacle.

35. A machine according to claim 32 in which said baffle surrounds said hollow member.

36. A machine according to claim 32 in which the baffle surrounds and is shaped similarly to said hollow member.

37. In a coating machine, a receptacle for liquid, a movably supported bearing positioned above said receptacle, a projecting device constructed and arranged to pick up liquid from the receptacle and project it upon a piece of work, said projecting device being supported upon a shaft in said bearing, and means for displacing said bearing to move the projecting device out of the receptacle to permit it to be cleaned.

38. In a coating machine, a receptacle for liquid, a frame supporting said receptacle, a bearing pivotally mounted on said frame above said receptacle, and a depending shaft in said bearing carrying at its lower end a projecting device dipping in the liquid in the receptacle constructed and arranged to project said liquid upon an article to be coated.

39. In a coating machine, a receptacle for liquid, a frame supporting said receptacle, a bearing pivotally mounted on said frame above said receptacle, a depending shaft in said bearing carrying at its lower end a projecting device dipping in the liquid in the receptacle constructed and arranged to project said liquid upon an article to be coated, and driving means for said shaft constructed and arranged to permit said pivotal movement of the projecting means without disturbing the driving connection.

40. In a cement applying machine, a support for an article to be coated, means for applying cement to a portion of an article on the support, and a plurality of shielding members mounted for movement toward and away from the article on the support substantially radially of said article and adapted to be brought into cooperative relation with the article to protect a portion thereof from the application of cement.

41. In a cement applying machine, a support for an article to be coated, means for applying cement to a portion of an article positioned on said support, and movable shielding means arranged in a ring and adapted to surround the article, said shielding means being mounted for movement with respect to said work support to bring said shielding means into cooperative relation with said article on the work support to pro-

- tect a portion of that article from the application of cement.
42. In a cement applying machine, a support for an article to be coated, means for applying cement to a portion of an article on the support, a plurality of shielding members mounted for movement toward and away from each other and the article on the support and adapted to be brought into cooperative relation with the article to protect a portion thereof from the application of cement, and means for moving said shielding members.
43. In a cement applying machine, a support for an article to be coated, means for applying cement to a plurality of sides of said article, a plurality of movable shielding means mounted for movement into positions around the article in cooperative relation with one another and the article to protect a portion of said article from the application of cement, and means for moving said shielding means.
44. In a cement applying machine, a receptacle for cement, a support for an article to be coated positioned above the cement receptacle, means for projecting cement on said article, shielding means movable severally into cooperative relation with the article to surround the article and to protect a portion of said article from the application of cement, and means for moving the shielding means toward and away from the article.
45. A machine for coating a limited portion of a shoe comprising fluid applying means and a shielding device to protect a portion of the shoe which is not to be coated, said shielding device comprising a plurality of plates arranged in a ring and relatively movable into cooperative relation with the shoe to surround the same.
46. A machine for coating a limited portion of a shoe comprising fluid applying means, a shielding device to protect a portion of the shoe which is not to be coated, said shielding device comprising a plurality of plates relatively movable into cooperative relation with the shoe, and means for adjusting one of said plates to make it conform to the shape of the shoe.
47. A machine for coating a limited portion of a shoe comprising fluid applying means and a shielding device to protect a portion of the shoe which is not to be coated, said shielding device comprising plates movable into cooperative relation with the shoe, one of said plates being flexible to conform to the shape of the shoe.
48. A machine for coating a limited portion of a shoe comprising fluid applying means and a shielding device to protect a portion of the shoe which is not to be coated, said shielding device comprising an end plate and movable means for supporting said plate permitting it to be wrapped around an end portion of the shoe.
49. A machine for coating a limited portion of a shoe comprising fluid applying means and a shielding device to protect a portion of the shoe which is not to be coated, said shielding device comprising a flexible plate supported at its ends and constructed and arranged to be wrapped around a portion of the shoe.
50. A machine for coating a limited portion of a shoe comprising fluid applying means and a shielding device to protect a portion of the shoe which is not to be coated, said shielding device comprising a series of flexible plates which surround the shoe and slope upwardly away from the shoe.
51. A machine for coating the foxing area of a shoe comprising fluid applying means and a shielding device to protect the upper of the shoe above the foxing area which is not to be coated, said shielding device comprising a series of overlapping inclined plates surrounding the shoe and having portions contacting with the shoe to define the upper limit of the foxing area.
52. A machine for coating the foxing area of a shoe comprising fluid applying means and a shielding device to protect from the application of cement the upper of the shoe above the foxing area, said shielding device comprising cooperating end and side plates, the lower edges of which contact with the shoe at the upper edge of the foxing area and slope upwardly away from the shoe.
53. A machine for coating a limited portion of a shoe comprising fluid applying means, a shielding device to protect a portion of the shoe which is not to be coated, said shielding device comprising a flexible plate and supporting means for said plate constructed and arranged to distort the plate upon engagement of one portion of said plate with the shoe thereby automatically to bring another portion thereof into engagement with the shoe.
54. A machine for coating a limited portion of a shoe comprising fluid applying means, a shielding device to protect a portion of the shoe which is not to be coated, said shielding device comprising a flexible plate, and means for bringing the median portion of the plate into engagement with a curved portion of the shoe and then distorting the plate to bring its end portions against the shoe.
55. A machine for coating a limited portion of a shoe comprising fluid applying means, a shielding device to protect a portion of the shoe which is not to be coated, said shielding device comprising a flexible plate, and operating means for bringing a portion of said plate into engagement with the end of the shoe operative also to bring another portion of said plate at the side of the shoe into engagement with the side of the shoe.

56. A machine for coating a limited portion of a shoe comprising fluid applying means and a shielding device to protect a portion of the shoe which is not to be coated, 5 said shielding device comprising a flexible plate separately supported at its center and end portions.

57. A machine for coating a limited portion of a shoe comprising fluid applying 10 means and a shielding device to protect a portion of the shoe which is not to be coated, said shielding device comprising a flexible plate supported at its center and end portions, and means for moving said center portion into engagement with the shoe ahead of the end portions.

58. A machine for coating a limited portion of a shoe comprising fluid applying means and a shielding device to protect a 20 portion of the shoe which is not to be coated, said shielding device comprising a flexible plate and supporting means for said plate constructed and arranged to press one portion resiliently against the shoe and then 25 upon continued movement to bring another portion into engagement with the shoe.

59. A machine for coating a limited portion of a shoe comprising fluid applying means and a shielding device to protect a 30 portion of the shoe which is not to be coated, said shielding device comprising a flexible plate for engagement with an end portion of the shoe, a slide for supporting said plate, and operating means resiliently connected to 35 said slide, said operating means being also resiliently connected to the end portions of the plate to wrap it around the end of the shoe.

60. A machine for coating a limited portion of a shoe comprising fluid applying 40 means and a shielding device to protect a portion of the shoe which is not to be coated, said machine comprising a frame having a slide and said shielding device comprising a flexible plate, the ends of which are loosely 45 connected to said slide.

61. A machine for coating a limited portion of a shoe comprising a frame, a slide on 50 said frame, fluid applying means, a shielding device comprising a flexible plate to protect a portion of the shoe which is not to be coated, and levers supporting the ends of said plate whereby movement of the slide will cause the shield to be wrapped around the 55 shoe.

62. A machine for coating a limited portion of a shoe comprising a frame, a slide on said frame, fluid applying means, a shielding device comprising a flexible plate to 60 protect a portion of the shoe which is not to be coated, levers on said slide supporting the ends of said plate, and resilient means tending to move said levers to open said flexible plate whereby upon movement of the guide 65 against the end movement of the slide to

bring the plate against an end portion of the shoe said plate will be wrapped around the shoe.

63. A machine for coating a limited portion of a shoe comprising a frame, a slide 70 mounted on said frame for movement substantially radially of the shoe toward and away therefrom, fluid applying means, and a shielding device to protect a portion of the shoe which is not to be coated, said shielding device being detachably secured to said slide and movable therewith into close coacting relation with the shoe. 75

64. A machine for coating a limited portion of a shoe comprising fluid applying 80 means and a shielding device to protect a portion of the shoe which is not to be coated, said shielding device comprising a distortable plate, and adjustable means for changing 85 the shape of said plate.

65. A machine for coating a limited portion of a shoe comprising fluid applying means and a shielding device to protect a portion of the shoe which is not to be coated, 90 said shielding device comprising a carrier, a distortable plate mounted on said carrier, and adjustable means on the carrier for distorting said plate.

66. A machine for coating a limited portion of a shoe comprising fluid applying 95 means and a shielding device to protect a portion of the shoe which is not to be coated, said shielding device comprising a carrier, a distortable plate mounted on the carrier, levers on said carrier bearing against the marginal portion of the plate, and means for independently adjusting said levers. 100

67. In a foxing cementing machine, a shoe support, cement applying means for projecting cement upon the foxing area of a shoe upon said support, and shielding means for protecting the shoe above the foxing area, 105 said shielding means comprising overlapping plates constructed and arranged for relative movement to surround a shoe. 110

68. In a foxing cementing machine, a shoe support, cement applying means for projecting cement upon the foxing area of a shoe upon said support, and shielding means 115 for protecting the shoe above the foxing area, said shielding means comprising overlapping plates constructed and arranged for relative movement to bring said plates into contact with a shoe thereby to define the upper edge 120 of the foxing area.

69. In a foxing cementing machine, a shoe support, cement applying means for projecting cement upon the foxing area of a shoe upon said support, and shielding means 125 for protecting the shoe above the foxing area, said shielding means comprising overlapping plates of flexible material constructed and arranged for relative movement and to be distorted to cause said plates to surround a 130

shoe in contact therewith, thereby to define the upper edge of the foxing area.

70. In a foxing cementing machine, a shoe support, cement applying means for projecting cement upon the foxing area of a shoe upon said support, and shielding means for protecting the shoe above the foxing area, said shielding means comprising overlapping side and end plates of flexible material constructed and arranged to be moved relatively to one another and to be distorted to surround a shoe to protect the upper of the shoe above the foxing area.

71. In a foxing cementing machine, a shoe support, cement applying means for projecting cement upon the foxing area of a shoe on said support, shielding means for protecting the shoe above the foxing area, said shielding device comprising slidably mounted side and end plates, and operating means constructed and arranged to move said plates into cooperative relation with a shoe thereby to surround the shoe above the foxing area.

72. In a foxing cementing machine, a shoe support, cement applying means for projecting cement upon the foxing area of a shoe on said support, shielding means for protecting the shoe above the foxing area, said shielding means comprising adjacent overlapping plates, movable supports for said plates, and common operating means for moving said supports to bring the plates into cooperative relation with one another and the shoe.

73. In a foxing cementing machine, a shoe support, cement applying means for projecting cement upon the foxing area of a shoe on said support, shielding means for protecting the shoe above the foxing area, said shielding means comprising adjacent overlapping plates, movable supports for said plates, and common operating means for moving said supports to bring the plates into cooperative relation with one another and the shoe, said common operating means comprising a resilient connection thereby to allow independent movement of the supports.

74. In a foxing cementing machine, a shoe support, cement applying means for projecting cement upon the foxing area of a shoe on said support, shielding means for protecting the shoe above the foxing area, said shielding means comprising oppositely movable slides positioned upon opposite sides of the shoe, plates on said slides adapted to be brought into co-operative relation with the sides of a shoe, and common operating means for moving said slides to carry said plates toward and away from the shoe.

75. In a foxing cementing machine, a shoe support, cement applying means for projecting cement upon the foxing area of a shoe on said support, shielding means for protecting the shoe above the foxing area, said shielding

means comprising pairs of slides mounted on opposite sides and opposite ends of a shoe on said support, shielding plates mounted on said slides, and common operating means for moving said slides to bring said plates into operative relation with said shoe, there being resilient connections between the operating means and the respective slides whereby independent movement of the slides is permitted.

76. In a foxing cementing machine, a shoe support, cement applying means for projecting cement upon the foxing area of a shoe on said support, shielding means for protecting the shoe above the foxing area, said shielding means comprising slides at the ends of a shoe on said support, flexible plates mounted on the respective slides, and means for moving said slides and associated flexible plates to cause each of the plates to be wrapped around respective end portions of said shoe.

77. In a machine for coating a limited portion of an article, fluid applying means constructed and arranged to project coating material upon the article, shielding means for surrounding and protecting a portion of the article which is not to be coated and having an article-receiving opening, and a support for the article to be coated positioned below said opening to hold the article in predetermined relation to said shielding means, said support being constructed and arranged for adjustment with respect to said shielding means thereby variably to determine the portion of the article which is to be coated.

78. In a machine for coating a limited portion of an article, fluid applying means constructed and arranged to project coating material upon the article, shielding means for protecting a portion of the article which is not to be coated and having an article-receiving opening, a support for the article to be coated to hold the same in predetermined relation to the edge of the opening in said shielding means, and means for tilting said work support to vary the relation of the article to the edge of the opening of said shielding means.

79. In a machine for coating a limited portion of an article, fluid applying means constructed and arranged to project a spray of coating material upon the article, shielding means for protecting from the spray a portion of the article which is not to be coated, a receptacle to receive surplus coating material, and a work support for the article to be coated positioned above the receptacle and below the shielding means, said work support comprising adjustable supporting means normally carrying one end of the support whereby the position of one end of the support may be varied with respect to the shielding means.

80. In a machine for coating a limited portion of an article, fluid applying means constructed and arranged to project coating ma-

- terial upon the article, shielding means for protecting a portion of the article which is not to be coated, a receptacle to receive surplus coating material, and a work support for the article to be coated positioned over said receptacle, said work support comprising an open grid, and means for adjusting the position of one end of said grid with respect to the other end and to the shielding means.
81. In a machine for coating a limited portion of an article, fluid applying means constructed and arranged to project coating material upon the article, shielding means for protecting a portion of the article which is not to be coated, a receptacle to receive surplus coating material, and a work support for the article to be coated, said work support comprising an apertured member and a work ejecting device movable through said work support for pushing a piece of work out of the machine after it has been coated.
82. In a machine for coating a limited portion of an article, fluid applying means constructed and arranged to project coating material upon the article, shielding means for protecting a portion of the article which is not to be coated, a receptacle to receive surplus coating material, and a work support for the article to be coated, said work support comprising a grid having recesses, an ejector received within the recesses of the work support, and means for elevating said ejector to lift the work out of the range of the applying means.
36. In testimony whereof I have signed my name to this specification.

FAY D. KINNEY.
